UNITED STATES PATENT OFFICE.

JACOB D. SCHAKEL AND JOSEPH RICE, OF CHICAGO, ILLINOIS, ASSIGNORS TO ELEVATOR COMPANY OF AMERICA, OF CHICAGO, ILLINOIS, A CORPORATION OF ILLINOIS.

SAFETY CUT-OUT SWITCH FOR ELEVATOR LOCKS.

Application filed November 15, 1922. Serial No. 601,136.

To all whom it may concern:

Be it known that we, JACOB D. SCHAKEL and JOSEPH RICE, citizens of the United States, residing at Chicago, in the county of Cook and State of Illinois, have invented a certain new and useful Improvement in Safety Cut-Out Switches for Elevator Locks, of which the following is a full, clear, concise, and exact description, reference being had to the accompanying drawings forming a part of this specification.

Our invention relates to safety cut out switch mechanisms for elevator door locks, and more particularly to a switching mechanism of this character that is inserted in an operating current circuit so as to break said circuit when the door is not securely locked. In elevator constructions, and particularly in an automatic elevator construction, it is very important that means is provided whereby it is impossible to operate an elevator when the door is unlocked. Some difficulty has been experienced in providing means for preventing the operation of the elevator when the door is not securely locked. In certain locking devices which have been previously provided, the difficulty has arisen that the circuit would be closed when the latch for the door was not held in position behind the abutment on the member mounted in the door frame, or hatchway, so that the door could be opened after the elevator has left the floor at which said door is located, thus making it possible for a person to open the door after the elevator has left the floor and walk into the shaft.

It is a purpose of the invention to provide a switching mechanism which is associated with a locking device in such a manner that the locking device must be in such position to securely lock the door before said switch is closed to complete the circuit through the same. This is particularly adapted for use with door locking mechanisms for automatic elevators that are operated in such a manner that the door cannot be unlocked unless the elevator is stopped opposite the floor at which the door is located.

It is a further purpose of the invention to provide a switching mechanism which is associated with a door latch that holds the door against movement relative to the casing in such a manner that the latch holds the switching device in circuit closing position when the latch is in engagement with

latching means in the casing or hatch, said switching mechanism having a normal tendency to move to open circuit position.

In the specific embodiment shown a contact member is provided which is movable into and out of circuit closing position, said member being movable out of circuit closing position by a resilient member and into circuit closing position by a member associated with a latch movable into and out of door holding position when said latch is in engagement with means to hold the door closed. The action of said means is substantially a snap action so as to close the switch at the instant when the latch drops into locking position and not prior thereto.

Other objects and advantages of the invention will appear as the description of the accompanying drawings proceeds. However, we desire to have it distinctly understood that we do not intend limit ourselves to the exact details shown or described but that we intend to include as part of our invention all such obvious changes and modifications of parts as would occur to a person skilled in this art and as would fall within the scope of the claims.

In the drawings:

Fig. 1 is a view partly in vertical section and partly in elevation showing my improved switching mechanism associated with a door lock;

Fig. 2 is a section taken on the line 2—2 of Fig. 1;

Fig. 3 is a section taken on the line 3—3 of Fig. 1;

Fig. 4 is a section taken on the line 4—4 of Fig. 1.

Referring in detail to the drawings, the invention is shown as comprising a casing 95 mounted in any suitable manner on the door casing or in the hatchway in a stationary position. The numeral 11 indicates a housing within which the latch is mounted, said housing 11 being secured in any suitable manner to the elevator door in such a position that the latch carried therein is adapted to cooperate properly with a suitable holding member in the casing 10 to hold said door in closed position. Within the housing 100 11 is mounted the latch member 12 which is adapted to pivot on the shaft 13, said member 12 being provided with a hook 14, which is provided with a shoulder at 15, said member 12 passing through the opening 16 in 110

the wall portion 17. The member 14 engages with the catch 18 having the abutment 19 thereon with which the shoulder 15 engages, the catch 18 being provided on the 5 locking member 20 pivotally mounted between the walls 21 of the casing 10, said pivot being designated by the numeral 22. The member 12 is provided with an upwardly extending arm 23 which has pivotally secured thereto the ear 24 carrying the pin 25 which is slidably mounted in the end wall 26 of the housing 11. Surrounding said rod 25 is a coil compression spring 27. The member 23 extends through a slot 28 in 10 the top of the housing 11 and is provided at the outer end thereof with a curved face 29 to provide a tapering end portion for said member 23 terminating in the rounded point 30. It will be seen that when the member 15 20 is raised, the spring 27 will be compressed, and the tendency will be for the member 23 to be swung in an anti-clockwise direction around the pivot 18 due to the action of the spring 27 to again force the end portion 14 of the locking member 12 into such a position that the shoulder 15 thereon 25 will engage with the member 20 to hold the door in closed position.

The casing 10 has an upwardly extending portion 31 which is provided with a transverse horizontally extending partition 32 to provide a switch chamber 33, said switch chamber having the conductors 34 and 35 extending into the same, said conductors 34 and 35 being serially included in the operating circuit for the elevator car. The member 34 leads to a binding screw 36 which is electrically connected with the conducting strip 37 mounted in any suitable manner as 30 by means of the bolt 38 on the block of insulation 39, said block of insulation 39 being mounted on the partition 32 by means of the bolt 40, a base member 67 being provided for said block 39. The 35 strip 37 terminates in a spring contact finger 41 which is arranged in opposed relationship to the spring contact point 42 provided on the conducting strip 43 which is secured on the block of insulation 39 by means of the bolt 44, said conducting strip being electrically connected with the binding screw 45 with which the conductor 35 is connected. Cooperating with the contact members 41 and 42 is a bridging contact member 46 40 which is mounted on the plunger 47 extending through the opening 48, said member 46 being insulated from the member 47 by a piece of insulating material 49.

The member 47 is pivotally connected with 45 one arm 50 of the bell crank lever 51 pivotally mounted on the shaft 52 extending outwardly from the boss 53 provided on the extension 31 of the casing 10. The other arm 54 of the bell crank lever 51 is pinned 50 by means of the pin 55 to the reciprocating

rod 56 extending through an opening 57 in the rear wall 58 of the casing 31, said member 56 having a collar or washer 59 thereon between which and the boss 60 extends the compression spring 61. The member 56 is 55 provided with a reduced threaded extension 62 extending through the opening 63 in the forward wall of the extension 31 of the casing 10, said extension 62 screwthreadedly receiving the block 64 and the nut 65 thereon. 75

It will be seen that due to this arrangement, the member 64 can be adjusted on the member 62 and locked in adjusted position by means of the member 65 so as to adjust the distance that the member 62 extends outwardly from the casing 31, so that the forward face 66 of the arm 23 can be so adjusted that the same will engage with the member 64 only to a sufficient degree to move the bell crank lever 51 to a position to cause 80 the contact 46 to bridge the gap between the contacts 41 and 42 when the member 12 is in such a position that the hook-like end portion 14 thereof is interlocked with the catch 18 to lock the door in closed position. 90 This being true also, because of the fact that there will be no engagement between the member 64, and the member 23 until the door is in closed position, as otherwise the front face 66 of the member 23 will not be in such 95 a position as to engage the member 64 sufficiently to move the contact 46 into bridging relationship relative to the contacts 41 and 42. Due to the provision of the spring 27, which is stronger than the spring 61, this action will take place substantially instantaneously when the door is in position to be locked and the locking member has dropped to locking relationship relative to the latch in the door casing. 105

The member 20 having the catch 18 is normally held in the position shown in Fig. 1 by the spring 69 and it will be seen that as the door is moved toward closing position the cam face 70 on the hook 14 will ride along 110 on the corner 71 of the hook 18 raising the member 12, so that the arm 23 will be thrown toward the right in Fig. 1 and will remain in such position until the shoulder 15 drops behind the abutment 19, at which time the 115 arm 23 engages with the block 64 to move the contact 46 to circuit closing position.

The member 20 has the extension 72 thereon against which the spring 69 bears, said extension engaging the forward wall of the casing 10 to limit the movement of the member 18 so that the same is in alignment with the face of the casing 10 toward the door. A lever 73 is pivotally mounted on the pivot 74 so as to be overbalanced toward the end 125 75 thereof, so that the same drops to the full line position thereof in Fig. 1 due to the action of gravity with the end 76 thereof engaging the extension 72 so as to prevent swinging of the member 20 on its pivot. 130

The member 73 is adapted to engage an adjustable stop 81 mounted on the bracket 82 to limit the downward movement thereof. The member 73 also serves as an armature 5 for the electromagnet 77, said electromagnet having a projection 78 thereon entering the opening 79 in the member 73 to guide the same. When the solenoids 77 are energized the member 73 is drawn up to the dotted 10 line position shown in Fig. 1, the member 20 is free to swing downwardly and the door carrying the casing 11 can be moved to the right, thus swinging the catch 18 downwardly out of engagement with the hook 14 as the door is moved away from the casing 15 and permitting opening of the door. The solenoids 77, as more clearly described in our application, Serial No. 526,752, filed Jan. 3, 1922, are energized when the door is closed, 20 the operating current of the elevator is off and the elevator car is opposite the floor at which the door that is to be opened is located. The other conditions having been carried out the circuit is completed by a 25 manually operated switch member operated at the floor, as described in said above mentioned application, only a portion of said mechanism being shown in this application to make the operation of the device clear. 30 Said switching mechanism is mounted in the casing 80 fixed in the hatch and comprises the member 86, the lower end 87 of which is adapted to move toward the left upon manual actuation of the switch, said member 86 35 having pivoted thereto the member 88 which carries the plunger 89 that extends through a suitable opening 90 in the locking member on the door, and which is adapted to engage with a plunger 91 mounted in the casing 110, 40 said plunger having a contact member 92 connected therewith which slides through the web 93, and between which and the plate 94 engaging the casing 95 is a coil compression spring 96. The member 94 is 45 mounted to move with the member 92. The contact member 92 engages with the contacts 97 and 98 which are in series with the circuit to complete the circuit through the solenoids 85 when the other necessary conditions to complete the circuit exist. 50

It will be seen that when the door is open, and the member 89 is moved away from in front of the member 91, the spring 96 acting against the plate 94 will move the same 55 to the position shown in Fig. 1, and the contact member 92 will be moved out of engagement with the contacts 97 and 98. Accordingly unless the door is closed, the spring 69 will hold the member 20 in an upward position 60 whether the manually operated switch member is operated or not, and only when the door is closed will it be possible to complete the circuit that breaks the joint at 75 so as to permit unlocking of the door. It 65 will accordingly be noted that when the door

is being closed, the spring will hold the member 20 in an upward position and the face 70 will have to ride up on the corner 71 before the hook 14 will move into locking position. Thus it will be impossible to operate the car, because the circuit will be broken at the contact 46, except when the lever 12 has dropped to the position shown in Fig. 1, and the door has been moved to closed position, so that the arm 23 will be in such a 75 position that the same will engage with the end of the member 64 as the member 12 drops downwardly into locking position. In unlocking the door the member 18 will drop due to the pull thereon by the hook 14, 80 but the operating circuit will be broken again by movement of the contact 46 as the door moves to the right, because the member 23 will move away from the block 64, although the same is not raised. 85

Under certain circumstances it may be desirable to have some form of manually operable means for unlocking the lock, for example, if the car should become stalled between floors it may be impossible to get out 90 of the hatch unless one of the doors could be manually opened. Accordingly a shaft 99 mounted in the casing 11 is provided which has a key receiving opening 100 therein, said shaft having the member 101 held in position 95 thereon by means of the set screw 102 so as to turn with said shaft 99. The member 101 is provided with a transversely extending portion 103 that is adapted to engage under the member 12 to raise the same 100 so as to raise the hook 14 out of interlocking relationship with the hook 18. Thus the door can be opened, however, as the member 12 is moved to such a position that the door 105 can be opened, the arm 23 will swing away from the block 64 and the spring 61 will move the contact member 46 out of circuit closing position, thus making it impossible to operate the car until the door is again closed and locked. 110

Having thus described our invention, what we desire to claim and secure by U. S. Letters Patent is:

1. In a device of the character described, a door, a casing for said door, an abutment in said casing, a latch on said door having a hook engaging said abutment for holding said door against movement relative to said casing, a switching device and a member on said latch movable in the direction of movement of said door to hold said switching device in circuit closing position when in locking engagement with said abutment. 115

2. In a device of the character described, a door, a casing for said door, an abutment in said casing, a latch on said door having a member engaging said abutment for holding said door against movement relative to said casing, a normally open switching device and a finger on said latch 125 130

engaging said switching device to hold the same in circuit closing position when in locking engagement with said abutment.

3. In a device of the character described, 5 a door, a casing for said door, an abutment in said casing, a latch on said door having a member engaging said abutment for holding said door against movement relative to said casing, a switching device and an arm 10 on said latch engaging said switching device to hold said switching device in circuit closing position when said latch is in locking engagement with said abutment.

4. In a device of the character described, 15 a door, a hatchway, a latch on said door adapted to engage means in said hatchway to hold said door against movement, means for holding said latch in engagement with said means in the hatchway, a switching device 20 comprising means for moving the same to open circuit position and a member associated with said latch and moving with said door for holding the same in circuit closing position when said latch engages said 25 means in said hatchway.

5. In a device of the character described, a door, a casing for said door, an abutment in said casing, a latch on said door engaging said abutment for holding said door 30 against movement relative to said casing, a switching device and means on said latch for holding said switching device in circuit closing position when in locking engagement with said abutment, said switch being in 35 open position until said door is closed and said latch is moved into position to securely hold said door against movement, said means moving in the direction of the movement of said door to open and close said switch.

40 6. In a device of the character described, a door, a lock for said door comprising a movable member mounted on the door casing, a latch on said door adapted to engage said member to hold said door against movement, means for holding said latch in engagement therewith, a switching device comprising means for moving the same to open circuit position and means associated with said latch for holding the same in circuit 45 closing position, when said latch engages said member, said switch being in open position until said latch is moved into position to securely hold said door against movement and means for holding said movable member against movement.

50 7. The combination with a switching device comprising a contact member movable into and out of circuit closing position, of means for moving said member out of circuit closing position, and means for holding said member in circuit closing position, said means comprising a door latch and a member moving with said latch in the direction of movement of said door engaging said 55 switching device to close the circuit only

when said latch is in final door latching position.

8. A device of the character described, comprising a contact member movable into and out of circuit closing position, a plunger, 70 means connecting said member and plunger, means for moving said member out of circuit closing position, and means engaging said plunger for holding said member in circuit closing position, said means comprising a door latch, an abutment with which said latch engages to hold said door closed, and a member moving with said latch engaging said plunger to move said contact member into circuit closing position only 75 when said latch and abutment firmly inter- 80 engage.

9. The combination with a switching device comprising a contact member movable into and out of circuit closing position, of 85 resilient means for moving said member out of circuit closing position, and means acting against said resilient means to hold said member in circuit closing position, said means comprising a door latch and a member 90 moving with said latch engaging said switching device to close the same only when said latch is in final door latching position.

10. In a device of the character described, 95 a switching device interposed in the elevator operating circuit comprising a contact member movable into and out of circuit closing position, means for moving said contact member out of circuit closing position and 100 means for moving said contact member into circuit closing position, said means comprising a door latch having a member moving therewith in the direction of movement of said door engaging said switching device to 105 close the same only when said door is closed and said latch is in final door latching position.

11. In a device of the character described, 110 a switching device interposed in the elevator operating circuit comprising a contact member movable into and out of circuit closing position, resilient means for moving said contact member out of circuit closing position and means for moving said contact member into circuit closing position, said 115 means comprising a door latch having a member extending therefrom engaging said switching device when said door is closed and said latch is in door latching position. 120

12. In a device of the character described, 125 a switching device interposed in the elevator operating circuit comprising a contact member movable into and out of circuit closing position, a reciprocable member connected therewith, resilient means for holding said reciprocable member in open circuit position, a door latch, and means associated with said latch engaging said reciprocable member to move the same to 130

circuit closing position when said door is closed and said latch is in latching position.

13. In a device of the character described, 5 a switching device interposed in the elevator operating circuit comprising a contact member movable into and out of circuit closing position, a reciprocable member connected therewith, resilient means for holding said reciprocable member in open circuit position, a door latch, and means associated with said latch engaging said reciprocable member to move the same to circuit closing position only when said door 10 is closed and said latch drops into latching position.

14. In a device of the character described, 20 a switching device interposed in the elevator operating circuit comprising a contact member movable into and out of circuit closing position, a reciprocable member connected therewith, resilient means for holding said reciprocable member in open circuit position, a door latch, and a member moving 25 with said latch, said reciprocable member projecting into the path of said last mentioned member, whereby said reciprocable member is moved to circuit closing position when said latch moves to door locking position.

15. In a device of the character described, 30 a switching device interposed in the elevator operating circuit comprising a contact member movable into and out of circuit closing position, a reciprocable member connected therewith, resilient means for holding said reciprocable member in open circuit position, a door latch, and a member moving with said latch, said reciprocable member projecting into the path of said last mentioned member and being adjustable, whereby said reciprocable member is moved to circuit closing position when said latch moves to door locking position.

16. In a device of the character described, 40 a switching device interposed in the elevator operating circuit comprising a contact member movable into and out of circuit closing position, a reciprocable member connected therewith, resilient means for holding said reciprocable member in open circuit position, a door latch, and a member moving with said latch, said reciprocable member projecting into the path of said last mentioned member, whereby said reciprocable member is moved to circuit closing position when said latch moves to door locking position, said latch and member moving therewith moving into door locking and circuit closing position with a snap action.

17. In a device of the character described,

a switching device interposed in the elevator operating circuit comprising a contact member movable into and out of circuit closing position, a reciprocable member connected therewith, resilient means for holding said reciprocable member in open circuit position, a door latch, an arm on said latch adapted to engage said reciprocable member, and spring means for moving said latch into door locking and said arm into switch actuating position.

18. The combination with an elevator door of a switching device interposed in the elevator operating circuit, an electric door lock and means for moving said switching device to open circuit position by opening movement of said door, said door lock unlocking said door only when the operating current is off, and said operating circuit being maintained open by said switching device until said lock locks said door.

19. The combination with an elevator door, of an electric door lock comprising a latch and a movable member normally held in position to interlock with said latch to hold said door against movement, a switch interposed in the elevator operating circuit, means for moving said switch to open circuit position, and means associated with said latch for closing said switch when said door is locked.

20. In a device of the character described, 55 a door, a casing for said door, a latch on said door for holding said door against movement relative to said casing, a switching device, means for moving said switching device to open circuit position and a member on said latch engaging said switching device to move said device to closed circuit position, said member being movable out of engagement with said switching device upon movement of said door toward open position without actuating said latch.

21. In a device of the character described, 100 a door, a casing for said door, a latch on said door for holding said door against movement relative to said casing, a switching device, means for moving said switching device to open circuit position and a member on said latch engaging said switching device to move said device to closed circuit position, said member being movable out of engagement with said switching device upon either raising said latch or opening said door upon movement of said door toward open position without actuating said latch.

In witness whereof, we hereunto subscribe 110
our names this 31st day of October A. D., 1922.

JACOB D. SCHAKEL.
JOSEPH RICE.
